UNITED STATES PATENT OFFICE.

DANIEL M. WINANS, OF BINGHAMTON, NEW YORK, ASSIGNOR TO THE BREWER-TITCHENER CORPORATION, OF CORTLAND, NEW YORK, A CORPORATION OF NEW YORK.

CURTAIN-ROD SOCKET.

Application filed January 21, 1924. Serial No. 687,401.

To all whom it may concern:

Be it known that I, DANIEL M. WINANS, a citizen of the United States, and a resident of Binghamton, and the county of 5 Broome and the State of New York, have invented certain new and useful Improvements in Curtain-Rod Sockets, of which the following is a specification.

My invention relates to a novel detachable curtain rod fastener or carrier for vehicle doors and the like, where it is desired to securely hold a curtain rod near the outermost end of a swinging door and provide support for the curtain thereon, and yet be 10 able to conveniently detach the rod at will.

The object of the present invention is to produce a neat and efficient curtain rod socket and a positive lock fastening means for inserted rod, more especially such as 15 are intended to be used in connection with a motor car or carriage door curtains.

It is the further object of this invention to provide for a concealed socket member that may be set into a recess formed in edge 20 of the head piece of the door frame, and to provide for a lever locking device for said socket adapted to engage and interlock with the inserted curtain rod, to the end that said rod is positively held in said socket and 25 prevented from lifting or turning until the lever is manipulated.

With these objects in view, the socket proper is preferably provided with an integral rib member projecting laterally from 30 the tubular part of the socket. These parts are adapted to lie flush with the face of the head piece and are neatly concealed behind an escutcheon plate. The projecting rib member may be suitably slotted to provide 35 for pivotally mounting the lever therein. When said lever is placed into longitudinal alignment with the rib, it snugly engages with a keyseat cut into the rod and locks the curtain rod in place.

40 The present invention therefore provides for an improved carrier means for quickly and positively locking or unlocking the curtain rod into its socket. Embodied herein are also other features of structure and arrangement of parts designed to facilitate the manufacture of said rod sockets and the application of same to door curtain rods, all of which will be set forth in detail hereinafter.

45 Reference is had to the accompanying

one sheet drawing which illustrates an example of the preferred form of my invention, like characters of reference indicating like parts in the several views, and in which drawing:

50 Fig. 1 represents a partial interior elevational view of an automobile body showing the door thereof equiped with my improved curtain rod socket device.

Fig. 2 is a detailed sectional view of the 55 assembled socket parts as taken along the line 2-2 of Fig. 1.

Fig. 3 shows a top or plan view of Fig. 2 as taken in partial section along the line 3-3.

Fig. 4 is a bottom view of Fig. 2 and shows further constructive details of the 60 socket member of this device.

Fig. 5 represents an elevational side view 65 of Fig. 2.

70 Referring first to Fig. 1, the hinged vehicle door 1 shown partially opened, is provided with the conventional lock handle 2 and a flat upper rail or head piece 3, suitably recessed to receive my socket device 80 which is designated in its entirety as 4. The lower edge of the side curtain 6 for the door is suitably fastened to the head piece 3, while one of the vertical edges of said curtain is flexibly attached to the extended portion of the jamb on the body part 5, whereby the door 1 and the curtain 6 are 85 allowed to open together in the customary manner. The unattached vertical edge of the side curtain 6 is intended to swing outward with the outermost end of the door, this portion of the curtain being supported by the bar or rod 7 in the usual manner and mounted within the fabric pocket 7a. As is best indicated in Fig. 5, the rod 7 is 90 preferably given a double bend to allow for the difference in alignment between the offset curtain plane and the axis of the inset rod socket.

95 As shown in Fig. 2, the lower portion of 100 the rod is loosely guided in the tubular socket member 4a. The rod end is undercut to provide for a squared support part 7b while the lower socket end is equiped with a registering shoulder lug 4b which projects 105 into and across the interior of the socket cavity and is adapted to abut the squared rod offset 7b. The purpose of the shoulder element of the lug is to give proper support to the rod and while the fitted vertical face 110

thereof prevents the bent rod 7 from turning about the socket axis. It will also be observed that the rod 7 is further provided with a rounded or dished keyseat 7_c which is 5 preferably milled into the rod surface, and the purpose of which will be more fully explained hereinafter.

It is preferred to provide the upper end portion of the socket 4_a with a relatively 10 thin and integrally formed flange part 4_e which in the present instance is shown as projecting at right angles from the socket cavity and serves as an escutcheon plate to conceal the remaining socket parts. The 15 underside of this flange is suitably reinforced against vertical deflection by the rib member 4_d which may also be formed integral and projects laterally from the socket cavity 4_a so as to terminate in the 20 dished cup part 4_e. A narrow slot or lever seat 4_f may be cut lengthwise of the rib to extend from the cup 4_e on a sloping angle toward the cavity of the socket for the purpose of snugly mounting the lock lever 8 25 therein.

When said slot is used, this lever may be pivotally mounted intermediate its ends about the fulcrum pin 8_a and so as to swing freely from its horizontal position lengthwise of the rib 4_d as shown in full lines, into its lifted oblique position as shown by dotted lines in Fig. 2. The short end of said lever disposed adjacent to the socket cavity 4_a is 30 suitably rounded with respect to the fulcrum 35 axis to constitute a lock-key as indicated at 8_b. This portion is preferably made to project into said socket contour to cooperate with the rod whenever the lever lies in its full-lined or flush position so that the key 40 end 8_b may then snugly engage the keyseat 7_c and become positively interlocked therewith in the manner shown in Fig. 2.

The other or free end of the lock lever 8 is provided with oppositely disposed side 45 lips such as 8_c which are adapted to drop into the circular contour of the cup 4_e while the outermost end of the lever together with said lips, are cut off squarely with respect to the lever axis and thus constitute a convenient manipulating edge for raising the lever into its disengaged position which is shown 50 dotted in Fig. 2.

When in this raised position, the rounded end of the lever designated as 8_b is thereby 55 fully withdrawn from the keyseat 7_c and this unlocked relation allows of freely lifting the rod 7 out of its socket whenever it is desired to remove the curtain 6 from the door 1.

60 It will be apparent that the spaced relation between the keyseat 7_c and the abutting shoulder faces formed between rod offset 7_b and the socket lug 4_b, is dependent upon the length of the socket tube 4_a used, and that 65 said keyseat is intended to properly align

with the rounded end of the lever end 8_b so as to allow of snug engagement with the keyseat 7_c whenever the lever is swung into its flush position.

As indicated in Fig. 2, the socket tube 4_a 70 is intended to be inserted into a hole formed into the top face of the door head piece 3. Said face is also preferably further recessed to permit of inserting the laterally disposed rib member 4_d therein while the 75 escutcheon plate or flange 4_e is made to overhang the edges of the recess so as to neatly trim the same. It will be evident that said opening in the head piece 3 is to be cut back and beveled where it meets the socket hole 80 to provide necessary clearance for the stipulated swinging of the lever 8.

Suitable fastening means such as the 85 wood screw 4_g, may be used to hold in place the socket device as a whole. It will be seen that the entire socket device is concealed within the door and behind the escutcheon plate 4_e. Furthermore the top edge of the lever 8 when placed in its locked position, is preferably made to lie flush with the exposed face of the escutcheon plate. Only a portion of the cup remains open and this is used for manipulating the lever end, all of which serves to give the top of the door a neat and finished appearance and otherwise 95 enhances the device for the purpose intended.

It will be understood that the novel socket carrier parts for door curtain rods as disclosed herein, are subject to modification in construction since the various parts, as an instance the escutcheon plate 4_e, need not be integrally formed as shown and various other changes in the details of my device may be resorted to without departing from the spirit and scope of my invention, hereinbefore described and more particularly set forth in the appended claims.

Claims:

1. In a curtain rod carrier, the combination of a socket, a rib-like member laterally disposed from the socket portion, an escutcheon plate serving to conceal and trim said parts, a rod adapted to be inserted into said socket, and means including a lock lever fulcrumed upon said rib-like member serving to positively lock said rod into the socket.

2. In a curtain rod carrier, the combination of a socket, a rib-like member laterally disposed from the socket, a rod adapted to be inserted into said socket, a lug means spanning the socket cavity and serving to support the inserted end of said rod, and means including a lever fulcrumed upon said rib-like member and adapted to positively lock said rod into the socket when the lever lies in substantial alignment with said rib member and to disengage said interlocking relation when the lever is swung 130

into oblique position with respect to said rib member.

3. In a curtain rod carrier, the combination of a socket, a rib-like member laterally disposed from the socket, a rod member adapted to be inserted into said socket, a lever slot for the rib member terminating in the socket cavity, a fulcrumed lock lever mounted in said slot having one end portion projecting into said cavity, a keyseat for the rod adapted to engage and interlock with the projecting end of said lever, and means for disengaging the projecting lever end from said keyseat.
- 10 4. In a curtain rod carrier, the combination of a socket, a rib-like member laterally disposed from the socket, a rod having its end portion disposed into a support part adapted to be inserted into said socket, a fulcrumed lock lever having a projecting end portion, a keyseat for said rod adapted to engage and interlock with said projecting lever end, a support lug for the socket adapted to register with said rod end and means for disengaging the projecting lever end from said keyseat.
- 15 5. In a curtain rod carrier for a vehicle door, the combination of a socket, a rib-like member laterally disposed from the socket, a rod adapted to be inserted into the socket, a fulcrumed lock lever having a projecting end portion, a keyseat for said rod adapted to engage and interlock with said projecting lever end, a door provided with a recess in the head piece adapted to receive said socket and rib parts, an escutcheon plate serving to cover the recess and conceal said socket and rib parts within said head piece, and means for holding said concealed parts in place.
- 20 6. In a curtain rod carrier, the combination of a socket, a rib-like member laterally disposed from the socket and terminating

in a cup part, a rod adapted to be inserted into the socket cavity, a lever slot extending from the cup part to the socket cavity, a fulcrumed lock lever mounted in the slot, said lever having one end portion projecting into the socket cavity and the other end provided with side lips adapted to drop into the cup recess, a keyseat for said rod adapted to engage and interlock said projecting lever end, and means for disengaging said lever end from said keyseat.

7. In a curtain rod carrier, the combination of a socket, an integral rib-like member laterally disposed from the socket, a rod member having its end portion formed into a support part adapted to be inserted into the cavity of said socket, a lock lever fulcrumed upon said rib-like member and of which lever one end portion is adapted to engage and interlock with said rod, a support lug for the socket adapted to register with said rod end and prevent rotation of the rod.

8. In a curtain rod carrier, the combination of a socket, a rib-like member laterally disposed from the socket, a rod member adapted to be inserted into the socket, a fulcrumed lock lever having a projecting end portion adapted to cooperate with the rod, a keyseat for said rod serving to engage and interlock with said projecting end when the lever lies in substantial alignment with said rib member and means for disengaging said projecting end from the rod seat when the lever is shifted into an oblique relation to the rib member.

In testimony whereof, I have herewith set my hand this 16th day of January, 1924.

DANIEL M. WINANS.
